DESIGN FOR A HIGHWAY SIGN

Albert Klotz, Vacaville, Calif.

Application April 14, 1934, Serial No. 51,404

Term of patent 14 years

To all whom it may concern:

Be it known that I, Albert Klotz, a citizen of the United States, residing at Vacaville, in the county of Solano and State of California, have invented a new, original, and ornamental Design for a Highway Sign, of which the following is a specification, reference being had to the accompanying drawing, forming part thereof.

Figure 1 is a view in front elevation of a highway sign, showing my new design.

Figure 2 is a view in rear elevation thereof.

Figure 3 is a side elevational view.

I claim:—

The ornamental design for a highway sign as shown.

ALBERT KLOTZ.
